COMBINED SOAP DISPENSER AND ASH TRAY

Burton L. Feinson, 275 Whitman Drive,
Brooklyn, N.Y. 11234

Filed July 11, 1968, Ser. No. 12,711

Term of patent 14 years

Int. Cl. D6—01

U.S. Cl. D33—26

FIG. 1

FIG. 2

FIG. 3

FIG. 4

FIG. 1 is a perspective of a combined soap dispenser and ash tray showing my design;

FIG. 2 is a top plan view thereof;

FIG. 3 is a front elevational view thereof; and

FIG. 4 is a side view thereof.

I claim:

The ornamental design for a combined soap dispenser and ash tray, substantially as shown and described.
